UNITED STATES PATENT OFFICE.

CHARLES C. FOLLETT, OF WATERVILLE, MAINE.

LUG-STRAP FOR LOOM PICKER-STICKS.

SPECIFICATION forming part of Letters Patent No. 408,703, dated August 13, 1889.

Application filed January 28, 1889. Serial No. 297,848. (No model.)

To all whom it may concern:

Be it known that I, CHARLES C. FOLLETT, a citizen of the United States, residing at Waterville, in the county of Kennebec and State 5 of Maine, have invented certain new and useful Improvements in Lug-Straps for Loom Picker-Sticks; and I do hereby declare the following to be a full, clear, and exact description of the invention, such as will enable others 10 skilled in the art to which it appertains to make and use the same.

My invention relates to lug-straps for loom picker-sticks, such as have hitherto been made of leather. These straps form the immediate 15 means by which the picker-stick is actuated, and they are secured to the end of a horizontal rod in such a way as to form a loop at the end, through which loop the picker-stick is passed. The strain on the lug-strap caused 20 by the sudden shock with which the picker-stick is projected forward is so great that it has always been necessary to use the best quality of leather, and in many looms the leather has been used of a double thickness. 25 The strain on the leather strap causes it to stretch and to increase in length, in consequence of which it must be frequently adjusted longitudinally to give the proper throw to the picker-stick. It is thus soon destroyed, 30 lasting on an average about six weeks.

The object of my invention is to construct a strap which shall be more strongly made and less liable to destruction than the leather strap already spoken of, and which shall at the same 35 time possess sufficient elasticity to do the work properly and to prevent breakage of the parts. It has always been thought that a very considerable degree of elasticity was necessary in the lug-strap to properly throw the picker-stick; but I find from experience that when 40 the motion is delivered to the picker-stick through the medium of a rigid strap having an elastic cushion at the point where the cushion takes place much better results are 45 obtained than by a more elastic strap.

My invention consists of a metal strap having a cushion of elastic material at the bend or heel.

In practice I prefer to make my strap in the 50 old way—of leather, with re-enforcing bands

of metal secured to the outside and extending lengthwise of the strap.

As shown hereinafter, there are several ways in which my invention can be carried out, and I do not wish to limit myself to any 55 particular form.

I illustrate in the accompanying drawings several forms of lug-strap made according to my invention.

In the drawings, Figure 1 is a side elevation 60 of one form of my strap in position in the loom. Fig. 2 is a perspective view of the same form of strap. Fig. 3 is a side elevation of another form. Fig. 4 is a perspective view of a third form. 65

A represents the leather strap, of ordinary form, having longitudinal slots *a*, for the passage of the bolt *e*, by which it is secured to the picker-rod *F*.

In the forms shown in Figs. 1 and 2 I secure the parallel metal straps *B* to the outside of the leather strap, one on each side of the slots *a*. The straps of metal are secured to the leather by means of staples *b*, which are clinched on the inside of the leather. By 70 this manner of securing the two parts together a little motion is allowed between the metal and the leather. 75

C represents the ordinary picker-stick, and D the loop attached thereto for supporting 80 the lug-strap. The washer *e'*, through which the bolt *e* passes, clamps the two straps *B* *B* solidly in place.

In Fig. 3 I show a form of strap made with the leather strap of the ordinary form, and 85 the metal strap constructed with two parallel bars and connecting-webs between them, all being formed in one piece.

In Fig. 4 I show the metal strap having the necessary slot for the passage of the bolt and 90 an elastic buffer or cushion *A'* in the bend or heel of the strap.

These various forms of my invention may be used as circumstances require.

I claim—

1. The lug-strap for loom picker-sticks, consisting of a metal bar bent or folded to form a loop, combined with a leather or other elastic lining for said strap extending from end to end thereof, substantially as shown. 95 100

2. The lug-strap for loom picker-sticks, consisting of a pair of metal bars bent or folded on their centers and embracing a single inner strap or lining of elastic material having longitudinal slots in its ends, said metal strap being secured to said inner strap, one at each side of said longitudinal slots, substantially as shown.

In testimony whereof I have hereunto set my hand, in the presence of two witnesses, to this 26th day of December, 1888.

CHARLES C. FOLLETT.
